UNITED STATES PATENT OFFICE

EDWARD F. PARKS, OF PROVIDENCE, RHODE ISLAND, ASSIGNOR TO UNIVERSAL WINDING COMPANY, OF BOSTON, MASSACHUSETTS, A CORPORATION OF MASSACHUSETTS

COP, CONE OR PACKAGE AND METHOD OF WINDING SAME

Application filed January 18, 1929. Serial No. 333,383.

This invention relates to an improved method of winding yarn, thread and other strand materials and to the cop, cone or package produced thereby. The invention is 5 more particularly concerned with the winding of yarn or thread for use as a supply in delivering a large number of ends from a creel or other holder in beaming, warping and other transfer processes.

10 One object of the invention is to provide a method of winding the yarn, thread or other material on friction or drum-driven winding machines without chafing or abrading the material under the frictional driving 55 contact on the package.

Another object of the invention is to provide a method of winding the yarn, thread or other material to package a given length or weight of the same with greater economy in 60 the time required for the winding operation.

Another object of the invention is to produce a cop, cone or package containing a continuous length of yarn, thread or other material which will deliver more freely and 65 uniformly in unwinding, with the tension on the strand maintained substantially constant.

Another object of the invention is to provide a cop, cone or package which may be so wound as to reduce the time required for 70 winding and which may be used in a magazine creel for supplying the material in continuous lengths without necessitating the stopping of the delivery to recreel fresh supplies.

Another object of the invention is to provide a cop, cone or package wherein the material is wound in separate units or individual 75 yarn bodies with the ends of the yarn joined together, and in which one unit may be displaced relatively to the other to facilitate the tying up or splicing of their ends.

Another object of the invention is to provide a cop, cone or package having the yarn wound in separate units of relatively short 80 traverse so that the material will deliver without undue resistance or hindrance from drawing across an extended surface of the package in unwinding over its end.

Another object of the invention is to provide a cop, cone or package in which the

yarn, thread or other material is wound in such manner that it will deliver freely over the end, first from one unit and then from another, without obstruction or restriction due to drag on the surface of the core or holder on which the material is contained. 55

Further objects of the improvement are set forth in the following specification which describes a preferred embodiment of the invention as illustrated by the accompanying 60 drawings. In the drawings:

Fig. 1 is a view showing the essential elements of a winding mechanism for producing the improved cop, cone or package, with the cop-holder or yarn-receiver shown in section 65 to illustrate an early stage in the process of winding the package thereon;

Fig. 2 is a view of the improved cop or cone shown as comprising two units and prepared for delivering the yarn therefrom in a continuous length; and 70

Fig. 3 is a view illustrating the method of supporting a plurality of the packages on a magazine creel to deliver the yarn continuously from the units of one package and then 75 from those of another with the delivery maintained continuous during the doffing and recreeling of fresh supplies.

The present invention, as before noted, relates more particularly to the winding of 80 yarn, thread or the like on so-called friction or drum-winders in which the package is rotated by frictional contact with a drive-roll or drum. The invention may also be 85 practiced, however, in connection with other types of winding machines in which the cop or package is wound on a positively driven spindle or mandrel.

In drum-driven winding machines the cop-holder or mandrel is constituted by a dead-spindle and the cop is built up on a suitable core, such as a paper tube or a wooden or fiber yarn-receiver of the required size and shape, rotatably supported thereon. At the 90 start of the winding the cop-tube or yarn-receiver is held in contact with the surface of the drive-roll or friction drum and as the 95 yarn is traversed longitudinally thereof to be wound thereon the carrier recedes from the 100

drum in accordance with the growth of the winding.

In the type of winding machine as herein illustrated, by way of example, 2 designates 5 the friction-drum or drive-roll which is represented as being supported on and rotated by a horizontal drive-shaft 3. The cop-holder or winding mandrel is shown as constituted by a dead-spindle 4 extending longitudinally of the drive-roll 3 and adapted to 10 be inclined with respect to the axis thereof to provide for winding cops or packages of conical form. The dead-spindle 4 is usually carried on a swinging arm or other movable 15 element 5 whereby it is adapted to recede from the drive-roll 2 during the growth in the winding. In the present illustration the spindle 4 carries a rotatable sleeve or bushing 6 which serves as a bearing or support 20 for the cop-tube or yarn-receiver C, to be later described. A collar 7, fixedly secured to the spindle 4, holds the sleeve 6 in place on the spindle, and a latch 8 of usual construction is pivoted to the outer end of the 25 spindle to provide means for holding the cop-tube or yarn-carrier C in place.

The yarn or other strand material is traversed longitudinally of the winding spindle by any suitable means, such, for instance, as 30 a reciprocating thread-guide. With the present improved method of winding I employ a plurality of thread-guides and, as shown in Fig. 1, two guides 10 are used in tandem form. Each guide 10 has a head 11 formed 35 with a slot 12 through which the strands y feed, and, preferably, a guard-hook or thread-retainer 13 extends across the groove in back of the guide to hold the strand in place.

40 The guides 10 have tubular bearing-portions 15 which are slidable on a horizontal traverse-rod 16 and above these bearings are forked portions 17 which embrace or hook across a track or guide-bar 18. The guides 45 10 have their bearing- or slide-portions 15 formed with lugs 19 which have threaded holes for receiving screws or studs 20 and 21. The two studs 20 and 21 are connected by a cross link 22 which couples the guides 50 10 together to be reciprocated as one. One guide 10 is provided with a bowl or roller 23 which may be rotatably supported on the end of the screw or stud 20. The bowl or roller 23 engages with a helical groove 24 in 55 a cam 25, a portion only of which is shown in Fig. 1, to provide means for reciprocating the guides in the manner as usually employed in winding machines of the present type.

60 In the practice of the improved method of winding in accordance with the present invention a novel form of cop-tube or yarn-receiver is employed as a core and support for the yarn package. The cop-tube or yarn-receiver may be of cylindrical form for use 65 in winding so-called parallel packages, or

it may be of conical shape as illustrated in the present drawings for use in winding tapered packages or cones of the type designed to afford a freer delivery of the yarn in unwinding over the end of the package. 70 In general, the cop-tube or yarn-receiver embodies a plurality of sections adapted to be assembled in axial alinement to be rotatably held on the winding-spindle or mandrel. Essentially, the several sections of the cop-tube or yarn-receiver are adapted to rotate 75 independently of each other for a purpose as later explained, and furthermore and most important, their peripheral surfaces, either of cylindrical or conical contour, are arranged in alinement, or one in continuation of the other.

As shown in Fig. 1, the cop-tube, core or 80 yarn-receiver C comprises two interfitting parts b and c, but in other instances it may have a greater number of sections. The main section of the core or carrier C consists of a butt b of frusto-conical shape provided with a tubular extension e projecting forwardly from its smaller end. The rearward or base end of the butt b is reduced somewhat in diameter and formed with a peripheral groove g which serves a purpose as later explained. The butt b is bored axially to provide a bearing f at the outer end of its extension e which is fitted to turn freely on the end of the dead-spindle 4. Rearwardly of the smaller bore or bearing f the extension e is counterbored at h to a diameter to adapt it to clear the spindle 4; and again at the rearmost end of the butt b is a still larger counterbore k adapted to fit over the rotatable sleeve or bushing 6 on the spindle. The base end of the butt b is further formed with a recess or counterbore l which provides a shoulder m adapted to bear against the shoul- 90 dered end of the enlarged portion 9 of the spindle 4, whereby the latter co-operates with the latch 8 to hold the cop-tube or carrier C from longitudinal movement on the spindle. 95

The other part or section c of the duplex carrier C is constructed as a sleeve having a central bore o of a size to adapt it to slide over the axial extension e of the butt b and to turn freely thereon. The periphery of the section c is tapered in accordance with the taper of the main section or butt b and is proportioned to adapt it to aline therewith when the two parts of the carrier are assembled in interconnected relation. The rearward or base end of the section c is provided with a reduced neck portion n which abuts the forward end of the butt b and is formed with a peripheral groove p adapted for a 100 purpose as later explained. The outer surface of the two sections b and c may be roughened or scored to form peripheral serrations s which act to grip the coils of yarn to prevent them from slipping or sliding 105 down the taper of the carrier. 110

As shown most clearly in Fig. 2, the cop, cone or package wound in accordance with the improved method of the present invention is built up in separate units or yarn bodies Y, Y surrounding the carrier sections b and c. The carrier C is placed on the spindle 4 with its parts in assembled relation and to start the winding operation the two ends of the thread or yarn y are supplied 5 from a suitable source and caused to feed through the grooves or notches 12 in the thread-guides 10. One end is wound around the base end of the butt b in the groove g as indicated at y' in Fig. 2, and the other end is 10 coiled or wound several times around the neck n of the section c within the groove p. A few turns of each end may then be taken around the peripheries of the sections b and c of the carrier C and the latter is then placed 15 with its surface in contact with the periphery of the drive-roll or drum 2 shown in Fig. 1. The drum 2 is usually driven continuously while the thread-guides 10 may also have a continuous reciprocation, and immediately 20 25 the cop-tube or carrier C is placed in contact with the drum it will be driven therefrom. As the carrier C is rotated from the drum 2 the two strands of yarn y will be wound onto the surface of the sections b and c while being 30 35 traversed to an extent proportionate to the length of the individual sections. It has been explained that the thread-guides 10 are reciprocated from the cam 25 which gives the same length of traverse to each and as the machine continues to operate the yarn will 40 be deposited on the carrier C in helical coils extending back and forth along the surfaces of the sections b and c and crossing each other at intervals in the well-known manner of a "crosswind".

It has been stated that the present invention not only provides for an improved method of delivering the yarn but that there is a decided advantage in the method of 45 winding the cop, cone or package and this improved feature will now be explained. It is well known that in winding conical packages the disparity in diameter between the larger or base end of the cone and its 50 apex end causes slippage between the periphery of the yarn mass and the surface of the drive-roll or drum from which it is rotated. The maximum traction on the drive-roll is at the base end of the cone where a 55 firmer contact is secured and with this end of the cone rotating at the same surface speed as that of the drum there must be a slippage at the apex end since the diameter of the drum is uniform throughout the length of its contacting surface while the diameter of the cone is variable. This unequal traction 60 between the surface of the yarn mass and the drum at the opposite ends of the cone, or in other words the slippage at the apex 65 end of the cone, results in subjecting a por-

tion of the yarn to undue friction and abrasion which has a deleterious effect, especially with fine, delicate materials. To relieve this frictional abrasive action on the yarn it has been a practice to construct the drum with 70 a slip-ring or loose sleeve adapted to turn independently of the driving end of the drum so as to accommodate its surface speed to the peripheral speed of the cone at the smaller end of the latter. With such an arrangement, 75 however, a certain proportion of the driving contact is lost, that is to say, traction will be effected only at the larger end of the cone and when the yarn mass approaches its maximum diameter there is apt to be slippage at 80 this end.

With the present improved construction of yarn-carrier having separately rotatable sections each yarn-body or unit of the cone is driven independently of the other and the difference in their surface speeds is therefore compensated for. Stated briefly, the butt b is driven at one speed in accordance with the diameter of the yarn mass being wound thereon and the other section c is 85 driven at a different speed in proportion to the diameter of its body of yarn. Through this provision the two yarn-bodies or units of the package are caused to make better contact with the surface of the drive-roll 2 without undue slippage and consequent abrasive action on the yarn being wound.

As the winding proceeds the yarn builds up in separate masses constituting the two units or yarn-bodies Y, Y as illustrated in 100 Fig. 2. After the winding has reached a predetermined diameter as required for a certain size of cone, cop or package the cop-holder is displaced to remove the cop from driving contact with the drum 2, automatically-operated stopping mechanism on the winding machine being usually employed for this purpose. At the completion of the winding operation the cop, cone or package is removed from its holder by withdrawing the cop-tube or yarn-carrier C from the spindle 4, the latch 8 being turned back into parallel 105 relation with the spindle to release the carrier.

The multi-unit cop, cone or package is prepared for delivering its yarn in a continuous length in the manner as next explained. After the yarn-carrier C has been removed from the cop-holder or winding-spindle its forward section c is withdrawn from the extension e on the butt b to permit access to the end of the strand y wound around the groove p in the neck n. A sufficient length of this yarn is unwound from the neck and its end tied or spliced to the leading end 115 from the yarn-body or unit Y wound on the butt b, the splice being indicated at x in Fig. 2. After the ends have been spliced or pieced up in this manner the carrier-section c is slid back into place on the extension e of 120 125 130

the butt *b* as shown in the view last referred to and the package is ready for use.

The winding machine usually comprises a plurality of winding mechanisms arranged in gang form and one operator may attend a large number of spindles which are maintained under continuous operation. The finished cops, cones or packages are taken from the winding machine to the location where they are to be creel to supply the yarn or thread to a warping machine or other apparatus used in the transfer process. Fig. 3 illustrates a section of a magazine creel which may be of the type described and illustrated in United States Letters Patent No. 1,660,299 issued February 21, 1928. This view shows the arrangement of two multi-unit or duplex cones arranged on holders 30 which are supported on uprights or standards 31 forming part of the grid-like framework of the creel. Each holder comprises an arm 32 which is swiveled on its upright 31 to adapt it to be swung back into convenient position for doffing the empty yarn-carrier and creeling a fresh cone, and means are provided for normally maintaining the holders 30 in operative position. The two associated holders of each pair have spindles 35 adapted for insertion into the bores of the cone-carriers C and provided with latches 36 at their ends for holding the packages in place. The axes of the spindles are inclined toward each other to converge at the yarn-receiving point of a tension-device 40, shown in plan view in Fig. 3 as attached to a vertical rod 41. As here illustrated, the tension-device comprises a frame or bracket 42 clamped to the rod 41 by means of a set-screw 43 and carrying a pin or stud 44 on which are held a pair of tension-disks 45. The leading end of the strand of thread or yarn *y* is led from the first cone of the pair through suitable guiding means 46 on the bracket 42, passed between the tension-disks 45 and around the stud 44, and led from the disks around a guide-hook 47. From the tension-device the strand draws to the warper or other machine to which the multiple ends from the supply packages on the creel are to be delivered. As the yarn is drawn through the tension-device it unwinds from the first unit *Y* on one cone and when the material in this body of yarn is exhausted the end delivers next from the second unit of the first cone or package until this latter body of yarn is completely unwound. As the body of yarn on the butt *b* is completely unwound the strand finally uncoils from the groove *g* at the base end of the butt and then delivers from the first unit *Y* of the next associated cone which is shown at the right in Fig. 3. While the yarn is delivering from the second supply the operator creels a fresh cone in place of the exhausted one and ties the leading end of the yarn from its first unit to the last end *y* wound in the

groove *g* at the end of the carrier C of the delivering cone. This process is repeated with respect to all the pairs of associated cones or packages on the creel so that the delivery is maintained continuous without stopping the warping machine or other apparatus to recreate fresh supplies.

It is to be observed that as the yarn unwinds from the multi-unit cone it is never required to draw across its surface for the full length of the package. That is to say, when the cone is full, or substantially so, and the yarn is unwinding at a relatively slow rate there will be less tendency for it to drag or catch on the surface of the cone because it does not have to draw across the whole length of the latter. This holds good with the strand unwinding from any one unit, and consequently a much freer delivery is obtained with less chance of straining or breaking the yarn due to resistance to its draft. As the yarn continues to unwind and the diameter of the yarn-body is reduced the strand will unwrap at a faster rate and this causes it to balloon outwardly so that it will not drag on the surface of the winding. Furthermore, when the strand is unwinding from the second yarn-body or unit on the carrier there will be no tendency for it to catch or drag across the forward section *c* of the carrier C because the periphery of the latter is in line or coincident with the periphery of the butt *b*. That is to say, even when the last coils are unwinding from the surface of the butt-section *b* there will be no tendency for the strand to catch on the rearward edge of the section *c* because the latter does not protrude beyond the diameter of the smaller end of the butt. This feature is important as eliminating any chance for straining or breaking the yarn during the delivery of the last coils from the surface of the cone-tube or yarn-carrier C.

It will be observed from the foregoing that the present invention provides an improved method of winding yarn, thread and other textile materials on a friction drive or drum-driven winding machine without the deleterious rubbing or abrasive action on the surface of the cone being wound.

The improved method of winding the cop, cone or package in separate units from a plurality of strands traversed simultaneously reduces the time required for the winding operation and thus increases the productive capacity of the winding machine.

The improved cop, cone or package, being composed of a plurality of units of relatively short traverse, provides for freer delivery of the material therefrom without undue resistance or hindrance from the drag of the strand across the surface of the package in unwinding over its end.

The improved form of sectional cop-tube or receiver for the package provides a convenient means for supporting the separate

yarn masses or units during the winding process and for thereafter disassembling the sections so that the first-wound ends of certain units may be tied to the leading ends of other 5 adjacent units.

The improved cop, cone or package is adapted to be used in multiple on a magazine type of creel to provide for the continuous delivery of a large number of ends to warp- 10 ing, beaming or other transfer processes without arresting the delivery for recreeling fresh supplies.

While I have herein described and shown the invention as applied to use in winding a 15 certain form of cop or package in the nature of a cone, it is to be understood that the size and shape of the package may be varied as desired and the steps in the process of winding it be changed to some extent without 20 departing from the spirit or scope of the invention. Therefore, without limiting myself in this respect, I claim:

1. An improved method of winding yarn, thread and other strand materials consisting 25 in providing a cop-tube composed of a plurality of interconnected but independently rotatable coaxial sections; rotatably supporting said cop-tube with its several sections in peripheral contact with a rotating drive-roll or drum; winding a package on the tube by simultaneously traversing a plurality of strands of the material to build a separate wound mass or unit on each section of the cop-tube; displacing the sections of the cop- 30 tube to recover the first-wound ends of the strands; splicing the first-wound end of the strand of one unit to the last wound-end from the next unit; and reassembling the 35 units in coaxial relationship to provide for the delivery of the material therefrom in a continuous length.

2. An improved method of winding a cone of yarn, thread or other strand material consisting in providing a conical cop-tube comprising a plurality of coaxial sections connected to adapt them to rotate independently of each other; rotatably supporting said cop-tube with its several sections in peripheral contact with a rotating drive-roll or drum; simultaneously traversing a plurality of strands to wind the material in separate masses surrounding the several sections of the cop-tube; displacing sections of the cop-tube to recover the first-wound ends of the 45 strands; and connecting the first-wound end of the strand of one mass to the last-wound end of an adjacent mass to provide for continuous delivery of the material from all of the units of the cone.

3. An improved package of strand material comprising a cop-tube composed of a plurality of coaxial sections, one section having a cylindrical extension projecting into the axial bore of the next section to adapt 50 said sections to be assembled for independent

rotation one in relation to another and for longitudinal displacement one with respect to another, the rearward end of one section having a reduced neck projecting axially therefrom and of less diameter than the adjacent end of the next rearward section to receive a reserve length of the strand wound therearound, and separate unitary masses of the material wound in adjacent relationship on the several sections of the tube with the 70 end of the reserve length of strand from one unit spliced to the leading end of the strand from the next adjacent unit to provide for continuous delivery of the material from all 75 the several units.

4. A cop of strand material comprising a cop-tube constituted by a plurality of coaxial sections, one section having a peripheral surface for receiving the strand material and a reduced axially-projecting cylindrical extension, another tube section bored to receive the axial projection on the first section to adapt it to be rotatively mounted thereon and having its periphery proportioned to form a continuation of the peripheral surface of the first section, said second section having a reduced neck projecting axially from its rearward end of less diameter than the end of the first section to receive a reserve length of 80 yarn wound therearound, and unitary masses of the material wound on the peripheries of the several sections with the reserve length of the strand from one unit spliced to the leading end of the strand from the next adjacent 85 unit.

5. A cop of strand material comprising a cop-tube constituted by a plurality of coaxial sections, one section having a tapering periphery and provided with an axially-arranged cylindrical extension, another section having a tapered periphery adapted to align with the periphery of the first section and bored axially to receive the cylindrical extension thereof, whereby said sections may be assembled to permit relative rotation 90 therebetween, said second section having a reduced neck projecting axially from its larger end and of less diameter than the adjacent end of the first section to receive a reserve length of yarn wound therearound, and unitary masses of the material wound on the several sections with the reserve length of strand from one unit spliced to the leading end of the strand from the next adjacent 95 unit.

In testimony whereof I hereunto affix my signature.

EDWARD F. PARKS.
